IRONING AND PRESSING MACHINE

Leo M. Kahn, New York, N. Y.

Application May 18, 1932, Serial No. 612,023

10 Claims. (Cl. 68—9)

This invention relates to laundry machinery and more particularly to reciprocating frictional ironers.

Among the objects of the invention are:

5 Provision of means for retaining articles to be ironed in the desired position when in the ironer to prevent undesirable creases.

10 Provision for ironing every portion of the article within the scope between the buck and head of the ironer inclusive of the space covered initially by the retaining means.

15 Provision for frictional movement between the buck and head members under pressure the movement being effected manually at leverage advantage.

Variation of pressure to be effected for various angles of oscillation of friction members.

20 Other objects as will be set forth or evident from the disclosure.

25 The invention accordingly comprises features of construction, combinations of elements and arrangement of parts which will be exemplified in the construction hereinafter set forth and the scope of the application of which will be indicated in the claims.

30 For a fuller understanding of the nature and objects of the invention, reference should be had to the following detailed description taken in connection with the accompanying drawings in which

Fig. 1 shows the ironer in side elevation;

Fig. 2 shows same in end elevation;

Fig. 3 is a sectional elevation view of the ironer while in operation.

35 Fig. 4 is a plan view of the retaining means

Fig. 5 is a diagrammatic representation of the scope of movement of the ironer and retaining members.

40 In the preferred construction, a frame 10 has a base 11 and a boom 12. A stand 13 is mounted on base 11 and fixedly secured thereto or adapted for sliding along guides 14 on the base 11. The stand 13 supports a buck 15, and the boom 12 carries a head member 16 to cooperate with the buck for ironing. The preferred manner of mounting the buck 15 on stand 13 is as follows:

45 Slidably mounted in vertical position within the stand 13 is a plunger 17, which is preferably rounded at the bottom and has a lug 18 at its upper extremity. The buck member 15 also has a pair of lugs 19 which are adapted to rotatably fit over a pin 20 passing through lug 18. The buck member 15, which has a handle 21 at one end thereof, is thus adapted to be oscillated about 55 pin 20 by moving the handle 21 up and down.

The rounded end of the plunger 17 is adapted to bear against a cam 22 keyed to the shaft 23 to which a lever 24 is also keyed so that the shaft may be rotated within the bearings 25 in the 60 stand 13. The preferred positioning of the cam

22 and lever 24 are such that when the lever is moved downward, the cam 22 forces the plunger 17 upward effecting pressure of the buck 15 against the head 16. When the lever 24 is in its upward position, the buck 15 is adapted to rest 65 on the supports 26, 26 which provide a firm support for the buck.

The head member 16 is pivotally mounted in the carriage 27 which is suspended from the boom 12, the rollers 28 permitting easy movement of the carriage to and from the operator by means of the handle 39. To provide for vertical displacement of the head member 16 when it is oscillated from the horizontal position, the head member 16 is slotted at the pin 29 about which it pivots and is 75 adapted to move against the action of a spring 30 preferably through the intermediary of a cap 31 slidably mounted in the carriage 27.

80 Preferably secured to one of the lugs 19 of the buck member 15 is a supporting frame 32 for the article retaining means 33. The retaining means comprises preferably a plurality of flat bottomed fingers 34 mounted on a shaft 35 in the bearing 36 on frame 32, and tied together by handle bars 37, 37 the shaft 35 being normally centrally maintained with respect to the frame 32 by means of the springs 38 which also apply the necessary pressure on the fingers. As shown in the drawing, the fingers 34 are preferably triangular in section, and a V-groove 40 is provided in the head 90 member 16 to wholly accommodate the fingers 34. A heater 41 is provided on the head member 16 for heating same, the heater being preferably an electric heating unit, the plug 42, connected by wire 43 to a source of electric power, being used as a 95 switch whereby to apply or shut off the heat.

The operation of the device is as follows:

95 Before pressing or ironing the garments, the buck member 15 is exposed for laying the garment, preferably by pushing the head member 16 back to the position indicated in dashed lines in Fig. 2; or the buck may be moved forward along the guides 14 to expose it for garment laying. The retaining means 33 is raised and swung back out of the way sufficient to overcome the action of the 100 springs 38, by being held in its raised position through the action of a stud 36, resiliently pressed by a spring 38 into a deep notch 32¹ in the shaft to hold the fingers against the torsion of springs 38 and the garment is spread on the buck. When 105 the garment has been properly laid on the buck the retaining member 33 is applied to the garment, all wrinkles are removed and the retaining fingers keep the garment in the desired position.

110 In the preferred mode of operation the head member 16 is then brought forward by means of the handle 39 so that the head member 16 is directly over the buck 15. Pressure is applied by moving the lever 24 down so that cam 22 raises the buck with the retaining fingers 34 and the 120

garment therebetween up against the head member 16, transmitting the pressure against the spring 30. In view of the balanced position of the fingers 34 by virtue of the springs 38, the grooves 5 40 are automatically in alignment with the fingers 34. Thus no wrinkles or creases are introduced into the garment as the head contacts the buck, because the fingers are not caused to be moved.

In this manner the garment is pressed while the heat is applied to the heater element 41. However, to obtain a finish or the equivalent of an ironer, all that is necessary is to move the handle 21 up and down several times, to obtain a friction movement of the head relative to the buck, whereby the 15 friction and heat accomplish the purpose of the ironer. When the operation is finished, the lever 24 is raised to drop the buck. It will be noted that during the oscillation, the fingers 34 are caused to move with the head while the garment is under pressure, so that the portions of the garment covered by the fingers 34 are likewise ironed. The Fig. 5, shows the displacement of the fingers between the two extreme positions of the oscillating movement.

25 It will also be noted that increase in the amplitude of oscillation causes greater compression of the spring 30 and the increased pressure effected is transmitted uniformly to the garment.

In this invention, the buck is readily movable 30 for applying pressure or for moving same into pressing alignment with the head, without danger of spoiling the position of the article on the buck with consequent possibility of forming undesirable creases. Once the retaining fingers are applied, the garment is held in position for all movements of the buck.

It will thus be seen that a simple, low cost structure is fully disclosed that is positive and simple in operation; that meets the requirements 40 of practical use and whereby the various objects of the invention are attained. Of course many changes in construction and arrangement of parts can be made without departing from the spirit of the invention. It is therefore intended that all 45 matter contained in this specification shall be interpreted as illustrative and not in a limiting sense, except as hereinafter claimed.

Accordingly what is claimed and desired to secure by Letters Patent is:

50 1. In a device of the class described in combination, a frame, a buck member and a head member each pivotally mounted, means for moving said buck member toward said head member for applying pressure to articles placed between 55 said members, and means for oscillating said members about their respective pivots for effecting frictional movement relative to each other.

2. In a friction press, in combination, a buck and a head, means for applying same to each other 60 and moving same in contact with each other, a plurality of fingers, means for positioning said fingers on said buck to retain articles on said buck in predetermined position, and openings within said head for accommodating said fingers, whereby movement of said head in contact with said buck will transmit said movement to said fingers, and spring means for maintaining 65 said fingers in alignment with said head openings when said head is out of contact with said buck.

3. In a friction press having a buck and a head, retaining means for articles placed on said buck, means for applying pressure to said buck and head, means for moving said buck and head past each other while under pressure and for moving said retaining means with said head member whereby the desired finish will be given to the entire article 70 within the scope of said buck and head.

4. In a friction press, in combination, a buck and a head, pivotal mountings for each, retaining means for articles placed on said buck, means for applying pressure to said buck and head, means on said head for engaging said retaining means, whereby oscillation of said head and buck members will effect lateral displacement of said retaining means.

5. In a pressing machine having a padded buck and a heated head, means for moving said head towards and from the buck, retaining means movable between the buck and the head in the same direction for engaging an article placed on the buck, openings in said head to accommodate said retaining means and means to hold said retaining means in and out of engagement with said article.

6. In an article retaining means for pressing machine having a padded buck and a heated head, 95 openings in said head to accommodate said retaining means when the head is placed in contact with said retaining means, means to bring the retaining means in position to hold an article placed on said buck and manual means to move same out of position from said article when the heated head is released.

7. In a work holding device for laundry pressing machine comprising a stationary padded buck and a heated head movable to and from said buck, retaining means movable in the same direction, and adapted to engage the article to be ironed before the head is brought into engagement, openings in said head to accommodate said retaining means, and means whereby the retaining means will be held in and out of engagement with said buck.

8. In a work holding device, a pressing machine comprising a padded buck and a heated head, means for bringing said head to and from the buck, work retaining means placed between said buck and head for engaging an article placed on the buck, grooves in said head for accommodating the work retaining means in such a manner that the surface of the heated head is continuous and means whereby said work retaining means can be held in and out of position with reference to work on the buck.

9. In a friction press, in combination, a buck and a head, means for applying same to each other and moving same in contact with each other, a plurality of fingers, means for positioning said fingers on said buck to retain articles on said buck in predetermined position, and openings within said head for accommodating said fingers, whereby movement of said head in contact with said buck will transmit said movement to said fingers, and spring means for maintaining said fingers in alignment with said head openings when said head is out of contact with said buck.

10. In a friction press having a buck and head movable into and out of contact with each other, the combination of a frame, a plurality of retaining members movable on said frame and positioned between said buck and head, openings in said head to accommodate said retaining members, means to allow said retaining members to move laterally and vertically with said head from a neutral position, and means to retain said members in a neutral position when said head is out of contact with said buck.
